UNITED STATES PATENT OFFICE.

WILLIAM A. READE, OF CLEVELAND, OHIO, ASSIGNOR TO THE LUDLOW TYPOGRAPH COMPANY, OF CLEVELAND, OHIO, A CORPORATION OF MAINE.

TYPOGRAPH MECHANISM.

1,226,007.

Specification of Letters Patent. Patented May 15, 1917.

Application filed August 20, 1915. Serial No. 46,499.

To all whom it may concern:

Be it known that I, WILLIAM A. READE, a citizen of the United States, and a resident of Cleveland, county of Cuyahoga, and State of Ohio, have invented a new and useful Improvement in Typograph Mechanism, of which the following is a specification, the principle of the invention being herein explained and the best mode in which

10 I have contemplated applying that principle, so as to distinguish it from other inventions.

The present invention more specifically consists in certain improvements in typograph mechanism of the kind shown and described in my co-pending application filed June 19, 1915, Serial No. 35,070. The object of such present improvements is to adapt such typograph mechanism for the casting of slugs or type bars having a length less than the length of the casting slot in the mold; indeed, it is possible with the arrangement of parts presently to be described, to cast individual type, or "sorts," 25 in any desired quantity, and with considerable rapidity. This is particularly advantageous, for the provision of an adequate stock of individual type of large sized characters is thus rendered possible for even a small printing shop. To the accomplishment of the foregoing and related ends, said invention, then, consists of the means hereinafter fully described and particularly pointed out in the claims.

35 The annexed drawing and the following description set forth in detail certain mechanism embodying the invention, such disclosed means constituting, however, but one of various mechanical forms in which the 40 principle of the invention may be used.

In said annexed drawing:

Figure 1 is a plan view of a broken portion of a typograph machine showing the parts of present interest; Fig. 2 is a transverse cross-section of the same on the line 2-2, Fig. 1; Fig. 3 is a similar section on the line 3-3, Fig. 1; Fig. 4 is a perspective view of one of the regular matrix bars used in the machine; Fig. 5 is a perspective view 50 of a matrix bar of special construction, which forms one of the characteristic features of the invention; and Figs. 6 and 7 are perspective views of a short type bar, and of an individual type formed with my 55 improved mechanism.

Of the casting mechanism proper, the only parts of present interest, or appearing in the drawing, comprise the mold 1, which it is understood is supported so as to be capable of vertical movement from the casting position shown in Figs. 2 and 3, to a position vertically below such illustrated position, so as to permit a slug or type-bar, formed therein, to be ejected. Coöoperative with such mold in the latter's casting position, is a suitable casting pot, of which only the nozzle 2, is shown, such pot being supported so as to permit the nozzle to be moved entirely out of the path of movement of the mold just described, and including suitable means, (not shown) whereby the molten metal may be forced into the casting slot 3 in the mold, when the latter is in proper position, as will be readily understood. The end of the nozzle is provided with a perforated plate 4, of usual construction, which comes into direct contact with the under side of the mold, the slot in the latter being of such form and dimensions as to serve as a mold for a slug body or type bar of the desired length and width.

In its casting position, the mold registers with, or rather lies in, an opening 5, in a horizontally extending top 6 of the general machine frame, so as to be substantially flush with the upper surface of such top, or rather with the surface of a trough-like depression 7, that extends transversely across the same. Associated with the mold, so as to be carried therewith in its vertical movement, is a trimming knife, or blade 8, in the form of a slide, such slidable trimmer blade being retracted in the casting position of the mold, but being capable of being advanced across the casting slot in such mold, after the nozzle of the casting pot has been withdrawn.

The extent and form of the top 6 are more or less a matter of indifference, such top primarily forming a support for a matrix holder 10, pending the placing of the same over the mold, and the withdrawal of the latter therefrom, when the slug has been cast. Such matrix holder is in the form of an independent member, arranged to receive and hold a number of detached matrix bars 11 (see Fig. 4) in selected relation, as shown in Fig. 1, thereby forming a composite matrix apart from, but adapted to coöperate with said casting mechanism.

Disposed alongside the trough or depression 7 in the top designed to receive successive matrix holders, as just set forth, is a lateral stop 12, that lies parallel with one side of the opening 5, wherewith the mold registers in its casting position. Beyond such stop 12 is a terminal stop-block 13 that projects over the trough 7 so as to engage the rear end of a holder 10 when the latter is disposed alongside such lateral stop 12; while adjacent the opposite side of the opening from such lateral stop, is a presser foot 14, adapted to force a holder closely against such stop 12. Finally, a vertically movable bar 15 (shown in Figs. 2 and 3), preferably having its lower edge rounded, is adapted to be brought down and vertically clamped on top of the body of matrices in the holder, when thus located and laterally clamped.

The holder 10, in the structural form illustrated, comprises two end pieces secured to side members of sufficient length to provide a rectangular opening somewhat larger than the maximum length of the slug which it is desired to cast. Slidably mounted between the side members is a block, or clamp member 16 that is engaged by the threaded portion of a screw 17, rotatably secured in the adjacent end piece, and provided with a knurled head, by rotation of which, said block can obviously be advanced or refracted to clamp the assembled matrix bars 11 or "matrices" as they are termed in the shop.

These bars are of the general form illustrated in Fig. 4, being, in effect, plates or blocks of uniform height, but of varying width, to accommodate character impressions 18 of correspondingly varying width. The latter are struck, or driven in the bottoms of recesses 19 cut in what may be called the lower edges of the bars, these recesses having in general, the dimensions which it is desired the head of the slug should have. The upper portions of the matrices project laterally in the form of ears 20, which are adapted to rest on the side pieces of the holder 10, leaving the bodies of the matrices depend between, and some distance below such side pieces, as shown in Fig. 3. It will be understood that where a blank, instead of a character, is desired in the slug to be cast, a matrix bar will be inserted, either with, or without a recess in its under face, but with no character impressions, so that the corresponding portion of the face of the slug will make no impression when set up in the printing press form.

In addition to such regular matrix bars, or "matrices," including in this term both those with character impressions and those without, I provide in the present instance, what may be termed "cut-off" bars 21, of the form clearly illustrated in Figs. 2 and 5. In other words, such special matrices, in-

stead of having recesses in their under faces, and carrying character impressions, are, on the contrary, provided with depending projections 22 of general rectangular form which are adapted to fit in the casting slot 70 of the mold, closely fitting the same transversely, and of a length equal to the depth of such slot. These bars 21 have otherwise the same general form and dimensions as the bars 11, including lateral ears 23 similar to the ears 20, before described.

It will be obvious that by the insertion of such a cut-off bar as has just been described, at any point in an assembled body of the regular matrices, the slug cast from such assembled body will be interrupted, or in other words, cut in two at the point of insertion of the projection 22 into the mold slot. Obviously also, as many such cut-off bars may be inserted in a line as desired, so as to cut up the slug into a series of short slugs, comprising for example single words, or even individual type, as illustrated in Figs. 6 and 7, respectively.

The manner in which the foregoing mechanism, including my improved cut-off bar is utilized in practice, has, it is believed, been already sufficiently explained, since the general casting operation as well as the trimming of the bottom of the slug after it has been cast, form no part of the present invention. In all kinds of display work and advertising matter, it is constantly necessary to employ slugs, or type-bars, that are shorter than standard column width, as, for example, to fill in beside cuts and inserts. With the ordinary Mergenthaler equipment, the only way to obtain such short slugs is either to adjust the mold, which obviously is feasible only where a large number of the short-length product is required, or to saw in two a regular slug, which is the common expedient, but an unsatisfactory one, because the interior of the slug body, as is well known, is always more or less hollow or spongy, only the outside shell being continuous and solid. Accordingly, when the slug is cut across, the cut end will not stand up in the form but tends to collapse, frequently causing serious trouble. Moreover, the cut ends, are always more or less rough, thus making fitting difficult.

All the foregoing objections are obviated by my present improved mechanism and method of casting short slugs, so that not only may the latter be made as expeditiously as the regular size, without bothering to change or adjust the mold, but the bodies of such short slugs are as complete and solid as those of regular size.

Other modes of applying the principle of my invention may be employed instead of the one explained, change being made as regards the mechanism herein disclosed, provided the means stated by any of the follow-

ing claims or the equivalent of such stated means be employed.

I therefore particularly point out and distinctly claim as my invention:—

- 5 1. In a typograph machine, the combination with a suitable holding member; of a set of detached matrix bars each having an edge adapted to coöperate with a mold, and oppositely extending lateral projections, said member being formed with an elongated opening adapted to receive and support a number of said bars in selected relation with such projections resting on the sides of said member, so as to form a composite matrix, the mold coöperative edges of said bars lying below the under face of said member when thus supported therein; and other bars provided with similar lateral projections and with other projections on their 10 mold coöperative edges adapted to extend from such composite matrix into the mold, substantially as described.
- 15 2. In a typograph machine, the combination with a suitable mold having a casting

slot, and a suitable holding member; of a set of detached matrix bars each having an edge adapted to coöperate with said mold, and oppositely extending lateral projections, said member being formed with an elongated opening adapted to receive and support a number of said bars in selected relation with such projections resting on the sides of said member, so as to form a composite matrix, the mold coöperative edges of said bars lying below the under face of said member when thus supported therein; and other bars provided with similar lateral projections and with other projections on their mold coöperative edges adapted to extend from such composite matrix into the mold, substantially as described.

Signed by me, this 18th day of August, 1915.

WILLIAM A. READE.
